UNITED STATES PATENT OFFICE.

EDWARD E. ELLIOTT, OF CHICAGO, ILLINOIS, ASSIGNOR TO MARSHALL FIELD & CO., OF ILLINOIS.

SKIRT.

SPECIFICATION forming part of Letters Patent No. 656,814, dated August 28, 1900.

Application filed October 4, 1899. Serial No. 732,446. (No model.)

To all whom it may concern:

Be it known that I, EDWARD E. ELLIOTT, a citizen of the United States, residing at Chicago, in the county of Cook, State of Illinois, 5 have invented a new and useful Improvement in Skirts, of which the following is a specification.

The object of my invention is to provide a skirt the waistband of which may be adjusted to different sizes without any alteration of the skirt itself.

It consists of details hereinafter described, and particularly pointed out in the claim.

Figure 1 is a perspective view of my skirt 15 with the waistband opened to its full extent. Fig. 2 is a similar view with the waistband drawn up closely.

A represents the skirt proper; B, the waistband; C, the lacing in the band; D, the buttons in the back.

The skirt portion is run straight up to the top of the waistband without seam or gathering, as shown in Fig. 1. The gathering or drawing up is accomplished entirely by the 25 lacing in the waistband. The waistband B is made in three separate sections sewed directly to the outside of the spread-out skirt, leaving a space between the ends of each section. Eyelets E are inserted at the ends of 30 B and lacing C put through them. Then as the lacings are drawn up the skirt is gath-

ered evenly on the different sides and the waistband is made to fit properly. The lacings are preferably so placed as to bring the gatherings one on each side over the hips and 35 one in either the front or back.

A placket and a row of buttons D are provided to enable the skirt to be removed and replaced.

In this manner I make a skirt which is simple, durable, and well fitting and can be readily adjusted to fit different-sized waists. 40

What I claim, and desire to secure by Letters Patent, is—

As a new article of manufacture, a skirt 45 having the skirt portion A extended continuous to the top without gathers or openings, except a placket, the waistband B permanently attached upon the outside of the waist portion of said skirt and divided into a plural- 50 ity of separate sections the aggregate length of said band-sections being considerably less than the circumferential length of the said continuous waist portion of the skirt, and means for adjustably securing the ends of 55 said band-sections together, substantially as described.

EDWARD E. ELLIOTT.
